HAT AND TIE HOLDER

Fred A. Reinke, Cleveland, Ohio

Application January 8, 1947, Serial No. 720,740

4 Claims. (Cl. 211—32)

1

This invention relates to a hat and tie holder and more particularly to a hat and tie holder of a portable nature.

The principal object of the invention is the provision of a device which may be attached to a door and will, in connection with the door, hold two hats and a number of neckties.

A further object of the invention is the provision of a hat and tie holder comprising a wire structure of a distortable shape to be adaptable to various sizes and shapes of hats.

A still further object of the invention is the provision of a hat and tie holder formed of a few component parts capable of being knocked down for shipment or handling and easily and quickly assembled for use.

The hat and tie holder shown and described herein has been designed to form a simple and efficient device for attachment to a door such as a clothes closet door to provide means for positioning two hats and a number of neckties in safe and secure location. The holder is attachable to the uppermost edge of the door by being hooked thereover and is primarily formed of two wire shapes, each of which is distortable so that they can be adjusted to fit various sized hats.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a front elevation of a hat and tie holder showing hats and ties thereon in dotted lines.

Figure 2 is a side elevation of the hat and tie holder showing a hat thereon in dotted lines.

By referring to the drawings and Figures 1 and 2 in particular, it will be seen that the hat and tie holder comprises a mounting bracket 10, the upper portion of which is of an inverted semi-U shape including a spaced downturned section 11 which is adapted to overlie the upper edge of a door, such as indicated by the numeral 12, so as to be positioned firmly thereon.

The lower portion of the mounting bracket 10 is formed with a flattened tubular socket 13 of a size sufficient to receive in side-by-side relationship a pair of wire body members 14. Each of

the pair of wire body members 14 is of a length sufficient to enable it to be shaped into a relatively large upright U-shape, as indicated by the numerals 15 in the drawings, and each of which is located outwardly away from the plane of the door 12, as best shown in Figure 2 of the drawings wherein the center panel of the door 12 is indicated by the numeral 16. The outermost ends of each of the pair of U-shapes 15 formed in the wire body members 14 are turned downwardly and inwardly so as to terminate at a central point immediately below the mounting bracket 10 and are then inturned, as indicated by the numerals 17, for reception in a spacing member 18. The spacing member 18 is preferably formed of rubber or other resilient material and includes an opening therein in which the two inturned ends 17 of the wire body members 14 may be positioned and held by frictional engagement. The opposite ends of the wire body members 14 are formed with a straight section and slightly outturned end portions 19 which normally overlie the uppermost portion of the tubular section 13 of the mounting bracket 10.

It will thus be seen that the hat and tie holder is formed of the four component parts; the mounting bracket 10, the two wire body members 14 and the spacing member 18. It will also be seen that the device may be completely disassembled by moving one of the straight end sections of the body members 14, normally lying within the tubular portion 13 of the mounting bracket 10, downwardly and out of the tubular portion 13 and subsequently disengaging the inturned end 17 of the body member 14 from the spacing member 18. The device may then be packed or carried in a more compact package than would otherwise be the case and is readily and easily assembled to form the device as illustrated in Figures 1 and 2 of the drawings.

In Figures 1 and 2 of the drawings the wire body members of the device are each illustrated as being covered with a continuous section of spirally wrapped plastic material and indicated by the numerals 20. This spirally wrapped plastic material 20 provides an attractive and serviceable covering for the wire body members and serves to protect hats and ties positioned in and hung on the device.

Still referring to Figures 1 and 2 of the drawings it will be observed that two hats 21 are represented by dotted lines as being positioned in the upright relatively large U-shapes 15 formed in the wire body members 14, and by referring to Figure 2 in particular it will be noted that the

brim portions of the hats 21 underlie the wire body members 12 and are positioned thereby adjacent the panel 16 of the door 12. The lower, interconnecting portions of the wire body members 14 provide straight sections over which a pair of neckties 22 are shown in dotted line representation. It will be obvious that more than two neckties can be positioned on this portion of the combination hat and tie holding device if desired.

It will also be obvious to those skilled in the art that the U-shaped bracket can be formed with a plurality of openings therein and without the portion adapted to overlie the top of the door so that it may be affixed to the surface of the door as by bolting or nailing the same thereto.

It will be obvious to those skilled in the art that the wire body members 14 can be covered with covering materials other than the plastic substance heretofore referred to. For example, enamels or paintlike finishes may be applied directly to the wire body members or they may be provided with a vulcanized rubber coating.

It will thus be seen that a simple and efficient hat and tie holder has been disclosed which may be economically formed, conveniently knocked down for shipment and readily assembled for use, and that it may be conveniently and easily secured to a door or other support by merely hooking the same over the upper edge of the door or support as the case may be.

It will thus be seen that the several objects of the invention have been met in the hat and tie holder disclosed herein.

Having thus described my invention, what I claim is:

1. A hat and tie holding device including an inverted U-shaped bracket attachable to the upper edge of a door and a wire body member depending therefrom having a pair of outturned arms defining relatively large U-shaped sections for the reception of hats, the outer ends of the said wire body member being brought together at a central point and a spacing member engaging ends of the wire body member and the said supporting door and positioning the hat and tie device away from the surface thereof.

2. A hat and tie holder comprising a bracket for mounting on a door and a distortable body member affixed to the said bracket, the said dis-

tortable body member being shaped into two oppositely disposed, semi-U-shapes and spaced away from the said door for the reception of hats, the outer ends of the said body member being brought together in a central location and a spacing member affixed thereto for spacing the said body member with respect to the said door.

3. A hat and tie holder comprising an inverted U-shaped bracket engageable over the upper edge of a door, a flattened tubular section on the said bracket, a pair of similarly formed distortable wire shapes, one end of each being positioned through the said flattened tubular portion of the said bracket and held thereby, the other ends of the said distortable wire shapes being engaged in a spacing member for holding the said wire shapes away from the surface of the said door, and the intermediate portions of the said wire shapes being shaped in relatively large U-shapes for the reception of the crown portions of two hats.

4. A hat and tie holder comprising an inverted U-shaped bracket engageable over the upper edge of a door, a flattened tubular section on the said bracket, a pair of similarly formed distortable wire shapes, one end of each being positioned through the said flattened tubular portion of the said bracket and held thereby, the other ends of the said distortable wire shapes being engaged in a spacing member for holding the said wire shapes away from the surface of the said door, and the intermediate portions of the said wire shapes being shaped in relatively large U-shapes for the reception of the crown portions of two hats, a covering material affixed to the said wire shapes and providing a surface for registry with the said hats.

FRED A. REINKE.
